UNITED STATES PATENT OFFICE.

ISIDORE T. REMAS, OF WOODHAVEN, NEW YORK, ASSIGNOR TO MERGENTHALER LINOTYPE COMPANY, A CORPORATION OF NEW YORK.

SLUG-CASTING MACHINE.

Application filed January 19, 1926. Serial No. 82,196.

My invention relates to slug casting machines, such as linotype machines of the general organization represented in U. S. Letters Patent No. 436,532, to O. Mergenthaler, wherein circulating matrices are released from a magazine in the order in which their characters are to appear in print, and then assembled in line, the composed line transferred to the face of a mold, the 10 mold filled with molten metal to form a slug or linotype against the matrices which produce the type characters thereon, and the matrices thereafter returned through distributing mechanism to the magazine from 15 which they started. In this class of machines, the molds are carried by a wheel or disc rotatably mounted on a slide commonly known as the "mold slide", which is advanced from the rear before each casting 20 operation to press the active mold against the composed line of matrices at the front. Usually, the advance of the slide is immediately followed by the advance of the melting pot, which brings its mouth-piece tight- 25 ly up against the back of the mold preparatory to the descent of the pump plunger and the casting of the slug. It has been found in practice that flakes or fins of type metal frequently form upon the mouth-piece 30 of the pot, and, if allowed to accumulate, result in imperfect lock-ups, back squirts, etc.

The present invention is directed to an 35 automatic wiper of improved form, which is operated after each casting operation to keep the pot mouthpiece clean and free of such metal accumulations. In the preferred embodiment illustrated, the wiper is arranged to be moved upwardly and downwardly across the face of the mouthpiece at 40 each operation, its movements in both directions being carried out in a positive manner and in timed relation to the other parts. More specifically, the wiper is operated from the main drive shaft of the machine, being secured to a rock shaft which is turned first 45 positively in one direction and then positively in the other by a projection on the mold disc rotating gear wheel through suitable connections to be described in detail later on.

In the accompanying drawings, I have shown my invention only in preferred form and by way of example and as applied to a 50 linotype machine, but obviously many

changes and alterations may be made therein and in its mode of operation without departure from its spirit. Generally speaking, I desire it to be understood that I do not wish to limit myself to any specific form 60 or embodiment, except in so far as such limitations are specified in the appended claims.

Referring to the drawings:

Fig. 1 is a perspective view of the improved wiper, its operating mechanism and associated parts; 65

Fig. 2 is a detail side view of the wiper operating cam and a portion of the gear wheel to which it is secured; 70

Fig. 3 is a detail vertical section through the wiper blade and its operating arm;

Fig. 4 is a vertical section, showing the means for turning the rock shaft in opposite directions; 75

Fig. 5 is a plan view of the parts shown in Fig. 4;

Fig. 6 is a vertical section, taken on line 6-6 of Fig. 5; and

Fig. 7 is a vertical sectional view, showing 80 the relative positions of the mold disc and mouthpiece in normal and casting positions.

As shown in Fig. 1, the wiper blade A is secured by screws *a* within the bifurcated end of a curved supporting arm A', which 85 is clamped securely at A² upon one end of a rock shaft B, the latter being loosely mounted in suitable bearing brackets C, C', so as to be rotatable in opposite directions. 90 to swing the wiper blade A from its normal position above the melting pot D downward across the mouthpiece D' and back again after each casting operation. A wiping pad A³ attached to the rear face of the blade A is in this way caused to sweep twice 95 across the face of the mouthpiece and remove any fins or flakes of metal which may have adhered thereto from a previous casting operation. In the commercial machines, the mouthpiece D' normally stands beneath or 100 within the flanged portion G' of the mold disc G or in juxtaposition to the back of the mold G² (see dotted lines in Fig. 7), so that the only time when the relative position of said parts is such that the face of 105 the mouthpiece may be reached by a wiper in the manner desired is after the pot D has receded, but before the mold disc has been retracted from casting position (see full lines in Fig. 7). Furthermore, in these ma- 110

chines, the recession of the pot is followed almost immediately by the retraction of the disc and, consequently, the downward and upward movements of the wiper must necessarily be effected within the time limit allowed in order to avoid being caught between said parts. It is therefore proposed, according to the present invention, not only to swing the wiper A downwardly across the mouthpiece by a positive action, but also to return it to its original position by a positive action.

To this end, means, controlled from the main shaft E, are provided for rocking the shaft B positively in opposite directions. As best shown in Figs. 1, 4 and 5, a lever B' is pivoted to the bearing bracket C and is loosely connected between its ends, as by a pin and slot arrangement B², to a yoke member B³ secured to the rock shaft B. The lever B' extends beneath the shaft B and is formed at its free end with a flat portion B⁴, which is so arranged that, when the shaft is turned in a clockwise direction, it will be rocked upwardly by the yoke B³ into the path of an inclined rib f of a cam plate F. This cam plate (Figs. 1, 2 and 4) is fastened to the side of the mold disc rotating gear wheel E' rigidly mounted on the main shaft E and normally rotated in the direction indicated by the arrows. A collar B⁶ loose on the rock shaft B, is provided on its periphery with an adjustable stud B⁵ and on its rear face with a fixed pin B⁷, the latter projecting into a circumferential recess B⁹ formed in a sleeve B⁸ keyed to the rock shaft. The recess B⁹ is of sufficient extent to permit a certain amount of relative movement between the collar B⁶ and shaft B, for reasons later to appear. The stud B⁵ is formed with a rounded anti-friction head B¹⁰, which (as shown in Figs. 1 and 4) is normally disposed in the path of the rib f of cam plate F.

According to the foregoing arrangement, the stud B⁵ will be first engaged by the inclined rib f of the cam plate F, as the wheel E' is rotated, and through the pin B⁷ and sleeve B⁸ turn the rock shaft B clockwise, the lever B' at the same time being swung upwardly through its connection with the yoke B³ into the path of the rib f (see dotted lines, Fig. 4). At this point in the operation, it will be noted that the rib f is about to ride over the stud head B¹⁰ and engage the lever end portion B⁴. As the rotation of the cam E' continues, the lever B' will be depressed to its original full-line position and through the yoke B³ turn the shaft B in the opposite or anti-clockwise direction, the rib f clearing the portion B⁴ as indicated by the dotted lines at the lower part of Fig. 4. The rock shaft B is thus operated positively in both directions in imparting the to-and-fro movements to the wiper

blade A, the extent of movement of the blade being readily determined by the position of the stud B⁵ and lever B' in relation to the cam plate F.

In order to prevent possible overthrow of the rock shaft B when it is turned in one direction by the lever B', as well as to obviate the sudden contact between the end of said lever and the stud B⁵ when the shaft completes its stroke in the opposite direction, there is provided a flat spring brake or detent B¹¹ anchored to the fixed bracket C and bearing down upon a second collar B¹² secured to the shaft B. This collar (as clearly indicated in Fig. 6) is formed on its peripheral edge with two ribs or tongues B¹³ adapted to alternately engage a corresponding groove in the under side of the detent B¹¹ as the shaft is rocked from one position to the other. The detent also serves to hold the wiper blade yieldingly in its normal raised position as shown in Fig. 1.

It may happen that, after the cam plate F has passed the stud B⁵ and depressed the lever B', some abnormal operation of the machine will necessitate a backing up or reversal of the main shaft E. In such case, the relative movement of the collar B⁶ to the shaft B, as permitted by the recess B⁹, allows the cam plate F to pass the stud B⁵ without interfering therewith.

Since the space available between the mold disc G and the pot mouthpiece D' is very limited, as may be observed by reference to Fig. 7, the wiper blade A is made comparatively thin and hence, without further support, might be subject to bending or facewise displacement such as to impair its parallel relation to the face of the mouthpiece. Means are therefore provided for guiding the wiper in its reciprocations to insure the proper frictional engagement of its wiping pad A³ with the front face of the mouthpiece D' at all times. Accordingly, the wiper blade A is formed near its free end with an upwardly curved guiding portion A⁴ having its inner edge A⁵ concentric with the axis of the rock shaft B. A guiding stud J, projecting rearwardly from a fixed part of the machine to a point flush with the front face of said portion A⁴, is also provided and arranged to restrain the blade against facewise displacement in a forward direction. The blade is likewise restrained against facewise displacement in a rearward direction by the head of a shouldered screw J' threaded into the end of the stud J. In other words, the relation of the parts is such that an annular groove is afforded to contain the inner edge A⁵ of the guiding portion A⁴.

Having thus described my invention, its construction and mode of operation, what I claim and desire to secure by Letters Patent of the United States, is as follows:

1. In a slug casting machine, the combination of a melting pot having a mouthpiece, a wiper blade arranged to swing back and forth across the face of the mouthpiece, guiding means to support the blade against lateral displacement during its movements, and means for imparting the to-and-fro movements to the wiper blade.

2. In a slug casting machine, the combination of the main shaft, a cam rigidly connected to said shaft, a melting pot having a mouthpiece, a wiper blade arranged to move back and forth across the face of the mouthpiece, and means actuated by the rigidly connected cam of the main shaft for moving the blade positively in both directions.

3. In a slug casting machine, the combination of the main shaft, a melting pot having a mouthpiece, a wiper blade arranged to swing back and forth across the face of the mouthpiece, guiding means to support the blade against lateral displacement during its movements, and means controlled from the main shaft for swinging the blade to and fro.

4. In a slug casting machine, the combination of the main shaft, a cam rigidly connected to said shaft, a melting pot having a mouthpiece, a wiper blade for the mouthpiece, a rock shaft whereon the blade is fixedly mounted, and means actuated by the rigidly connected cam of the main shaft for turning the rock shaft positively in both directions to swing the wiper blade back and forth across the face of the mouthpiece.

5. In a slug casting machine, the combination of the main shaft, a cam rigidly connected to said shaft, a melting pot having a mouthpiece, a wiper blade for the mouthpiece, a rock shaft whereon the blade is fixedly mounted, and means actuated by the rigidly connected cam of the main shaft for turning the rock shaft positively in both directions to swing the wiper blade back and forth across the face of the mouthpiece, said means being arranged to permit the backing up of the main shaft when desired.

6. In a slug casting machine, the combination of the main shaft, a melting pot having a mouthpiece, a wiper blade for the mouthpiece, a rock shaft whereon the blade is fixedly mounted, means controlled from the main shaft for turning the rock shaft in both directions to move the wiper blade back and forth across the face of the mouthpiece, and yielding means for restraining the blade against overthrow movement and for holding it in inactive position.

7. In a slug casting machine, the combination of a melting pot having a mouthpiece, a wiper blade for the mouthpiece, a rock shaft whereon the blade is fixedly mounted, a rotary operating member having a cam projection thereon, and means connected to the rock shaft and operable by

said projection to turn the shaft first positively in one direction and then positively in the other direction to swing the blade back and forth across the face of the mouthpiece.

8. In a slug casting machine, the combination of a pot mouthpiece wiper blade, a rotary operating member, a rock shaft upon which the wiper blade is mounted, a cam projection secured to the operating member, a stud protruding from the shaft and arranged in the path of said projection whereby the shaft is partially rotated in one direction, and a lever for turning the latter in the opposite direction, said lever being normally located out of the path of said projection and arranged to be moved into the path thereof by said partial rotation of the shaft.

9. In a slug casting machine, the combination of the pot mouthpiece wiper blade, a rock shaft upon which it is mounted, a yoke fast to the rock shaft, a pivoted lever connected between its ends to the yoke, a collar mounted on and operatively connected to the rock shaft, a stud protruding from the collar, and a rotary wheel provided with a cam projection adapted to engage first the stud and then the free end of the lever in the rotation of the wheel.

10. In a slug casting machine, the combination of the wiper blade A and its operating arm A', the rock shaft B to which the arm A' is secured, the yoke B³ fast to the rock shaft, the pivoted lever B' connected as at B² to the yoke B³ and provided with the end portion B⁴, the collar B⁶ loose on the rock shaft and provided with the radially protruding stud B⁵ and the laterally projecting pin B⁷, the collar B⁸ fast to the rock shaft and formed with the circumferential recess B⁹ in which the pin B⁷ engages, and the rotary wheel E' provided with the cam plate F with its inclined rib f, all substantially as shown and described.

11. In a slug casting machine, the combination of the wiper blade A and its operating arm A', the rock shaft B to which the arm A' is secured, the yoke B³ fast to the rock shaft, the pivoted lever B' connected as at B² to the yoke B³ and provided with the end portion B⁴, the collar B⁶ loose on the rock shaft and provided with the radially protruding stud B⁵ and the laterally projecting pin B⁷, the collar B⁸ fast to the rock shaft and formed with the circumferential recess B⁹ in which the pin B⁷ engages, a collar B¹² also fast to the rock shaft and formed with the locking ribs B¹³, the spring detent B¹¹ formed with a notch to engage the ribs B¹³, and the rotary wheel E' provided with the cam plate F with its inclined rib f, all substantially as shown and described.

12. In a slug casting machine, the combination of the vibratory wiper blade A

formed with the curved guiding portion A⁴, and the grooved collar J with which the guiding portion A⁴ is operatively engaged.

13. In a slug casting machine, the combination of a swinging pot mouthpiece wiper blade, a rock shaft on which the wiper blade is mounted at one end, means for turning the rock shaft in opposite directions to swing the wiper blade to and fro, and guiding means engaged with the free end of the wiper blade to support it against lateral displacement in its swinging movements.

14. In a slug casting machine, the combination of a melting pot having a mouthpiece, a wiper blade arranged to move back and forth across the face of the mouthpiece, two sets of devices operatively connected to said wiper blade, the devices of one set being actuatable to move the blade positively in one direction, and the devices of the other set being actuatable to move the blade positively in the opposite direction, and posi-

tively acting means arranged to engage and actuate the two said sets of devices one after the other in rapid succession in imparting the to and fro movement to the wiper blade.

15. In a slug casting machine, the combination of a melting pot having a mouthpiece, a wiper blade for the mouthpiece, a rock shaft whereon the blade is fixedly mounted, two sets of devices operatively connected to said rock shaft, the devices of one set being actuatable to turn the shaft positively in one direction and the devices of the other set being actuatable to turn the shaft positively in the opposite direction, and positively acting means arranged to engage and actuate the two said sets of devices one after the other in rapid succession in causing the wiper blade to swing back and forth across the face of the mouthpiece.

In testimony whereof, I have affixed my signature hereto.

ISIDORE T. REMAS.
